CHARLES E. MILLER, OF INDIANAPOLIS, INDIANA.

Letters Patent No. 80,651, dated August 4, 1868.

IMPROVEMENT IN WASH-BOILERS.

The Schedule referred to in these Letters Patent and making part of the same.

TO ALL WHOM IT MAY CONCERN:

Be it known that I, CHARLES E. MILLER, of Indianapolis, Marion county, Indiana, have invented a certain new and useful Wash-Boiler; and I do hereby declare the following to be a full, clear, and exact description thereof, reference being had to the accompanying drawings, making part of this specification.

This is an improvement in the class of wash-boilers in which the suds, being subjected to a forced circulation, and expelled through suitable spouts upon the clothes, a very effective detergent action is secured.

The improvement over my patent, granted June 23, 1868, consists in employing, instead of the perforated bottom, raised pit-covers, having imperforate tops and perforated sides, by which means I prevent the stoppage of the perforations by the mass of clothes, and also reduce the liability of a reflux of water upward through the boiler-bottom.

Figure 1 is a longitudinal section through a wash-boiler, provided with my improvements.

Figure 2 is a perspective view of one of my spouts detached.

A represents a common oval wash-boiler, of the kind having two drops or pits, B B', to enter the boiler-openings of the stove.

To each pit there is fitted a device which I call the spout C or C', which spout, although fitting tightly within the pit when in use, is susceptible of being readily lifted out of the pit when so desired.

Each spout is composed of the following parts: D is a cover to the pit, consisting of a disk, d, and rim d', the former, in conjunction with the rim, screwing to close the opening of the pit, and the rim itself having, just underneath the disk, a series of apertures, d'', which afford a communication from the body of the boiler into the spout at this part. A raised head, d''', on the rim d', limits the entrance of said rim into the pit.

E is a perforated diaphragm, which is so fixed within the spout as to extend obliquely across the pit, in the manner represented.

The office of the perforated diaphragm E, besides that of passing the cold returning water through its apertures e, is to direct the heated and ascending suds into the pipe or column G, which extends upwards, with a gradually-contracted area within the boiler, to nearly the top thereof. The top of the pipe G is closed, as shown, and said pipe is provided, near its top, with two necks, g g', to which are fitted the nozzles or spouts proper, H H', of which each is capable of being directed more or less upward or downward, so as to cause the jet of suds to strike such portion of the clothes as may be desired. These adjustable nozzles may be substantially such as are described in my patent of 23d of June, 1868.

The operation of my boiler is as follows: Each pit having been momentarily uncovered by lifting the spout, a small piece of soap is placed in each pit, and the spout returned to its place. The clothes (preferably presoaked) are then packed into the boiler, as shown, and water poured in, in quantity sufficient to cover them. As the water becomes heated, it rises within each pit, and, striking the oblique diaphragm E, is by it deflected toward that side of the pit which is nearest the pipe G, up whose narrowing interior it rises, with constantly-accelerated velocity, to escape upon the surface of the clothes in the form of jets of considerable force.

The water, as fast as heated, escaping from the pits, its place is supplied by the colder water, which, having percolated through the substance of the clothes, enters the pits through the apertures d'' and e, to be again heated and expelled in the manner already described.

It will be seen that the detachability of the spouts and nozzles enables any portion to be inspected and cleansed, and also enables the boiler to be used in the customary form, whenever so desired.

The situation of the apertures d'' on the sides of the spouts, and under the overhanging disk d, is highly advantageous in several respects.

Being removed from direct contact with the clothes, the latter are not liable to be streaked with rust, or torn by contact with the edges of the apertures, nor are they liable to be drawn into said apertures by the motion of the descending current, so as to partially or wholly close the apertures, and thus stop the circulation of suds.

I have selected for illustration the form of spout which practical test has proved to be effectual, but do not desire to restrict myself to the precise form here represented; for example, an inferior modification of my invention may have discharge-nozzles projecting rigidly from the pipe, instead of being adjustable, as here shown.

I claim herein as new, and of my invention—

The arrangement of cover D, having perforated rim d' and unperforated top d, oblique and perforated diaphragm E, pipe G, and nozzles g g', substantially as set forth.

In testimony of which invention, I hereunto set my hand.

CHARLES E. MILLER.
